Assistant Examiner — Jae Liang

(57) **CLAIM**

The ornamental design for an infuser bottle, as shown and described.

DESCRIPTION

FIG. 1 is a front perspective view of an infuser bottle showing my new design;

FIG. 2 is a bottom perspective view thereof;

FIG. 3 is a front view thereof;

FIG. 4 is a rear view thereof;

FIG. 5 is a right-side view thereof;

FIG. 6 is a left-side view thereof;

FIG. 7 is a top plan view thereof; and,

FIG. 8 is a bottom plan view thereof.

The broken lines in the drawings depict portions of the infuser bottle that form no part of the claimed design.
